GAME APPARATUS

Harry W. Standridge, Chicago, Ill.

Application October 13, 1933, Serial No. 693,504

6 Claims. (Cl. 273—94)

This invention relates to certain improvements in game apparatus of the type disclosed in my co-pending application for U. S. Letters Patent Serial Number 511,577, filed January 27, 1931, 5 and the present application is a continuation, in part, of such co-pending application.

More particularly, the present invention comprehends the provision of a game apparatus essentially embodying a playing field consisting of 10 a sheet of cardboard or other suitable material having suitable recesses or openings therein in the open spaces thereof or considerably spaced from the edges and corners of the same, and each and all of said edges and corners of said field being 15 free from any recess or opening therein so as to permit the operation of playing elements thereon in the manner hereinafter described, in combination with a plurality of visually distinguished groups of spherical playing elements 20 adapted to be moved by gravity upon and over said field and to be brought to positions of rest in said recesses or openings of the field, the relative sizes of such recesses or openings in the field and said playing elements being such that any 25 playing element resting in any one of said recesses or openings may be dislodged therefrom but will also resist dislodgment therefrom in a certain manner and to a certain extent. More 30 particularly, the relative sizes of the recesses or openings and the playing elements is such that a playing element resting in one of said openings in the field may be dislodged therefrom by having rolled against it one or more of the remaining playing elements without the field being tipped 35 sufficiently so that the tipping alone will cause such dislodgment, each of said playing elements and openings shown in the drawings being, respectively, three-eighths and three-sixteenths of an inch in diameter. At the same time, the contact of an unlodged playing element against a lodged playing element will not cause the latter to be dislodged unless the former is rolled 40 some distance to acquire considerable momentum before such contact, the location of the openings or recesses a considerable distance from the edges 45 and corners of the playing field permitting such distant rolling of the unlodged playing element for that purpose. Still further, the relative sizes of the recesses or openings and the playing elements is such that a lodged playing element will resist dislodgment to the extent that when the field is tipped only sufficiently to cause unlodged 50 playing elements to be moved thereover, the weight of an unlodged playing element resting against the lodged playing element will not cause 55

the latter to be dislodged. It is especially important to this particular operation that the recesses or openings in the field be positioned in the open spaces thereof or spaced considerably from the edges and corners of the same, so that each 5 and all of said edges and corners of the field will be free from any recess or opening and all of the playing elements may be operated in the manner described and also simultaneously have access to and in mass formation crowd about and around 10 said openings, and so that such playing elements when lodged in said openings, will both resist and be subject to dislodgment therefrom as described.

The present invention further comprehends the 15 provision of a game characterized as specified above in which the recesses or openings in the field are so spaced apart that when any two of 20 said playing elements are resting in any two adjacent recesses or openings in the field, the distance between such two playing elements is less than the diameter of the respective playing elements, so that any other unlodged playing element cannot pass between said two lodged playing elements as long as they remain lodged or "hold" 25 their position of rest or lodgment in the recesses or openings.

The invention further contemplates provision of the openings in a line and spaced as described above so that when certain of the playing elements are lodged in all of the openings of the line, none of the remaining unlodged playing elements can pass through said line or between adjacent lodged playing elements, as long as each lodged playing 30 element in the line remains lodged or holds its 35 position. By the provision of the combination of elements of the form and relation above described, opportunity is especially afforded for skillful manipulation of the game board so as to cause the playing elements to simulate to an interesting 40 degree certain plays which occur in the actual game of football wherein the holding of a line of players in certain defensive positions is important and dependent upon the exercise of great 45 ability and skill.

The outer edges of the field and the ends and sides may be raised for the purpose of retaining the playing elements thereon, or said field may be placed in a box or other receptacle whose side and end walls may serve the purpose of retaining 50 the playing elements on the field.

The present invention consists of the novel form, combination and arrangement of elements and parts hereinafter more fully described, shown 55 in the accompanying drawings and claimed.

In the drawings:

Figure 1 is a plan view of one form of game apparatus embodying the present invention.

Figure 2 is a transverse section on line 2—2 of Figure 1.

Figure 3 is a view similar to Figure 1 of another form of game apparatus embodying the present invention.

Figure 4 is a transverse section on the plane of line 4—4 of Figure 3.

The game apparatus forming the subject matter of the present invention may be constructed from any suitable material, and may also vary in size and design without departing from the inventive idea. The apparatus, however, essentially embodies a playing field 5 or 5a having openings 6 or recesses 6a therein, in combination with playing elements, of the character to be presently described, and walls 7 around the playing field to retain the playing elements thereon.

In the form of the invention shown in Figures 1 and 2, the playing field 5 consists of a sheet removably fitted within and supported upon the bottom of a shallow box or tray 8 whose ends and sides form the walls 7 around the field to retain the playing elements thereon. The openings 6 in the field 5 of Figures 1 and 2 extend wholly through such field, and a second removable playing field 5b having differently located openings 6b may also be removably fitted within the box 8 to provide for simulation of additional plays in the game of football by the use of the apparatus, it being apparent that either playing field 5 or 5b can be placed uppermost for use within the box 8.

Also, as illustrated in Figures 3 to 5 inclusive, the bottom wall of the box 8a may serve as the playing field 5a, in which case the places or positions of rest for the playing elements will preferably consist in the recesses or openings 6a extending only partially through the bottom wall of the box 8a.

The game further embodies a group of eleven playing elements 9 of one color and a second group of eleven playing elements 10 of another color, together with a still further single playing element 11 of a third color, designed to represent respectively the players of opposing football teams and the football on a football playing field. Similar playing elements of the form of game shown in Figures 3 to 5 inclusive are respectively indicated at 9a, 10a and 11a.

Centrally located in each playing field is one of the openings 6 or 6b or one of the recesses 6a surrounded by a circle indicated at 12 in Figure 1, at 12b in Figure 3, and at 12a in Figure 5, designed respectively for lodgment of the associated football simulating playing element 11 or 11a therein.

In the form of the playing field shown in Figures 1 and 5, the central opening 6 or recess 6a is surrounded by the remaining openings or recesses with the latter arranged in an orbital or continuous line and eleven in number to have the eleven playing elements of one of the groups of playing elements lodged therein. This continuous line of openings or recesses encloses a space within which may be assembled the eleven playing elements of the other group in surrounding relation to the associated football simulating playing element when the latter is arranged within the central opening or recess. It will be noted that the openings or recesses of this continuous line are uniformly and so spaced apart that no playing element can pass between any two playing elements lodged in any two adjacent ones

of the openings or recesses of this continuous line. Thus, when the playing elements of one group occupy all of the openings or recesses of the continuous line, neither the football indicating playing element nor any one of the playing elements of the other group assembled within said continuous line can be rolled outside of the latter as long as the playing elements resting in the openings or recesses of said continuous line hold their positions of rest or lodgment. In view of the fact that the playing elements resting in the openings or recesses of the continuous line may only be dislodged and will also resist dislodgment to the extent hereinbefore described, the formation of the playing elements of one group in said circular line and the capturing of said playing elements of the other group around the ball inside said line affords opportunity for the exercise of extraordinary skill. As in the actual game of football, each and all of the playing elements in the operation of this apparatus, in mixed or unmixed formations or masses, may be moved slowly or rapidly about the open spaces of the playing field while having access to and being variously crowded into and out of the openings or recesses designed for their lodgment. Thus, phenomenal skill may be exercised in lodging the playing elements in the positions designed for them, and at the same time in succeeding in causing the respective playing elements to hold the positions so designed for them. The playing field may be suitably marked off in yard lines and provided with suitable representations of goals at opposite ends of the playing field simply to complete the realistic appearance of the playing field.

Before play starts all playing elements are assembled in the corners and at or near the edges of the field, and each and all of said playing elements must be free from lodgment in any of said openings. During play it is necessary for the practical operation of the games to operate said playing elements in the manner herein described without having any of them encounter an opening in said corners or along the edges of said field. During play, also, each and all of said playing elements which are free from lodgment in any of said openings, or as many of them as are necessary, either separately or in a group, is or are "steadied" against the wall or walls, or against each other, in the corners or at the edges of said field, and in and from such position or positions is or are aimed at and rolled against, and thus dislodge, one or more improperly lodged playing elements. It is therefore necessary that there shall be no openings in the corners or along the edges of said field.

By this method of operation, which is thus made possible by the construction described, all of such playing elements shown in Fig. 2 may be properly positioned in less than one minute, and all of those shown in Figs. 1 and 3 may be properly positioned in less than two minutes.

An unlodged playing element may also be operated in a like manner by first being steadied against two playing elements lodged in openings in the field, thus being in a better position to dislodge an improperly lodged playing element than when steadied otherwise as above described. By such method of operation, which is made possible by the construction herein described, all of the playing elements can be properly positioned with great rapidity such as is impossible of accomplishment by any previous method known. With the diameter of each opening one-

half of the diameter of each playing element, the 5
utmost efficiency in said method of operation is
made possible, and either diminishing or increasing
the relative diameter of the openings or the
playing elements proportionately lessens such ef-
ficiency. Therefore, the practical accomplish-
ment of such operation requires that the diameter
of each opening shall be more than one-
third and less than two-thirds of the diameter
10 of each of the playing elements, and preferably
one-half the diameter of such playing elements.

What I claim as new is:

1. In a game, the combination of a playing
field bounded by walls to retain playing elements
15 thereon and having openings extending wholly
or partially therethrough, and a plurality of visually
distinguished groups of spherical playing
elements adapted to be moved by gravity upon
and over said field to effect predetermined lodg-
20 ment of playing elements in said openings, the
relative sizes of such openings in said field and of
said playing elements being such that a playing
element resting in one of said openings in said
field may be dislodged therefrom by having rolled
25 against it one or more of said other playing
elements without tipping said field sufficiently so
that said tipping alone will cause such dislodg-
ment, while said playing element will also resist
dislodgment to the extent that when said field
30 is tipped only sufficiently to cause unlodged play-
ing elements to be moved thereover the weight
of an unlodged playing element resting against
the lodged playing element will not cause the lat-
ter to be dislodged, and such that the contact of
35 an unlodged playing element against the lodged
playing element will not cause dislodgment of the
latter unless the former is rolled some distance
before such contact, said openings in said field
being so positioned that each and all of the cor-
40 ners and edges of said field are free from opening
therein and so that the space between each of
said openings and the ends or sides of said field
is sufficient for one or more of said unlodged
playing elements to be rolled therein against a
45 playing element lodged in any of said openings
with sufficient force to dislodge said playing ele-
ment therefrom in the manner described.

2. In a game, the combination of a playing
field bounded by walls to retain playing elements
50 thereon and having openings extending wholly or
partially therethrough, and a plurality of visually
distinguished groups of spherical playing elements
adapted to be moved by gravity upon and
over said field to effect predetermined lodgment
55 of playing elements in said openings, the relative
sizes of such openings in said field and of said
playing elements being such that a playing element
resting in one of said openings in said field may
be dislodged therefrom by having rolled
60 against it one or more of said other playing
elements without tipping said field sufficiently
so that said tipping alone will cause such dislodg-
ment, while said playing element will also resist
dislodgment to the extent that when said field
65 is tipped only sufficiently to cause unlodged play-
ing elements to be moved thereover the weight
of an unlodged playing element resting against
the lodged playing element will not cause the lat-
ter to be dislodged, and such that the contact of
70 an unlodged playing element against the lodged
playing element will not cause dislodgment of the
latter unless the former is rolled some dis-
tance before such contact, said openings in said
field being so positioned that each and all of the
75 corners and edges of said field are free from

opening therein and so that the space between
each of said openings and the ends or sides of
said field is sufficient for one or more of said
unlodged playing elements to be rolled therein
against a playing element lodged in any of said
openings with sufficient force to dislodge said
playing element therefrom in the manner de-
scribed, and certain of said openings in said field
being so spaced apart that when two of said play-
ing elements are resting in two of such adjacent
openings in said field the distance between such
two playing elements is less than the diameter of
each of the other playing elements, as shown and
for the purpose described.

3. In a game, the combination of a playing
field bounded by walls to retain playing elements
15 thereon and having openings extending wholly or
partially therethrough, and a plurality of visually
distinguished groups of spherical playing elements
adapted to be moved by gravity upon and
over said field to effect predetermined lodgment of
20 playing elements in said openings, the relative
sizes of such openings in said field and of said
playing elements being such that a playing element
resting in one of said openings in said field
may be dislodged therefrom by having rolled
25 against it one or more of said other playing
elements without tipping said field sufficiently so
that said tipping alone will cause such dislodg-
ment, while said playing element will also resist
dislodgment to the extent that when said field
30 is tipped only sufficiently to cause unlodged play-
ing elements to be moved thereover the weight
of an unlodged playing element resting against
the lodged playing element will not cause the lat-
ter to be dislodged, and such that the contact of
35 an unlodged playing element against the lodged
playing element will not cause dislodgment of the
latter unless the former is rolled some dis-
tance before such contact, said openings in said
field being so positioned that the space between
40 each of said openings and the ends or sides of
said field is sufficient for one or more of said
unlodged playing elements to be rolled therein
against a playing element lodged in any of said
openings with sufficient force to dislodge said
45 playing element therefrom in the manner de-
scribed, and certain of said openings in said field
being so spaced apart that when two of said
playing elements are resting in two of such adjac-
ent openings in said field the distance between
50 such two playing elements is less than the diam-
eter of each of the other playing elements, and
said certain openings so spaced apart forming a
continuous line in which openings one group
of playing elements may rest, and there being
55 sufficient space inside said line to assemble one
or more groups of other playing elements therein,
as shown and described.

4. In a game, the combination of a playing
field bounded by walls to retain playing elements
thereon and having openings extending wholly or
partially therethrough, and a plurality of visually
distinguished groups of spherical playing elements
adapted to be moved by gravity upon and
over said field upon tilting thereof to effect pre-
65 determined lodgment of playing elements in said
openings, the diameter of each of such openings
being more than one-third and less than two-
thirds of the diameter of each of said playing ele-
ments, and said openings being so positioned that
70 each and all of the corners and edges of said field
are free from any of said openings and so that the
space between each of said openings and the ends
or sides of said field is sufficient for one or more
75

of said unlodged playing elements to be rolled therein and against a playing element lodged in any of said openings with sufficient force to dislodge said playing element therefrom in the manner and substantially as described.

5. In a game, the combination of a playing field bounded by walls to retain playing elements thereon and having openings extending wholly or partially therethrough, and a plurality of visually distinguished groups of spherical playing elements adapted to be moved by gravity upon and over said field upon tilting thereof to effect predetermined lodgment of playing elements in said openings, the diameter of each of such openings 10 being more than one-third and less than two-thirds of the diameter of each of said playing elements, and said openings being so positioned that each and all of the corners and edges of said field are free from any of said openings and so that the 15 space between each of said openings and the ends or sides of said field is sufficient for one or more of said unlodged playing elements to be rolled therein and against a playing element lodged in any of said openings with sufficient force to dislodge said playing element therefrom in the manner described, and certain of said openings in said field being so spaced apart that when two of said playing elements are resting in two of such adjacent openings in said field the distance between 20 such two playing elements is less than the diameter of each of the other playing elements, substantially as shown and for the purpose described.

6. In a game, the combination of a playing

field bounded by walls to retain playing elements thereon and having openings extending wholly or partially therethrough, and a plurality of visually distinguished groups of spherical playing elements adapted to be moved by gravity upon and over said field upon tilting thereof to effect predetermined lodgment of playing elements in said openings, the diameter of each of said openings being more than one-third and less than two-thirds of the diameter of each of said playing elements, and said openings being so positioned that each and all of the corners and edges of said field are free from any of said openings and so that the space between each of said openings and the ends or sides of said field is sufficient for one or more of said unlodged playing elements to be rolled therein and against a playing element lodged in any of said openings with sufficient force to dislodge said playing element therefrom in the manner described, certain of said openings in said field being so spaced apart that when two of said playing elements are resting in two of such adjacent openings in said field the distance between such two playing elements is less than the diameter of each of the other playing elements, and said certain openings so spaced apart forming a continuous line in which openings one group of playing elements may rest, and there being sufficient space inside said line to assemble one or more groups of other playing elements therein, substantially as shown and described.

HARRY W. STANDIDGE.
